ATTORNEYS

UNITED STATES PATENT OFFICE.

GUSTAV ADOLPH STREHLKE, OF MORTON GROVE, ILLINOIS.

MEANS FOR COOLING REFRIGERATORS.

Application filed January 29, 1925. Serial No. 5,612.

My invention relates to means for cooling in refrigerators, and it consists in the combinations, constructions, and arrangements herein described and claimed.

5 An object of my invention is to provide an economical means for cooling a refrigerator during the cool months of the year by means of which it is unnecessary to employ artificial cooling mediums.

10 A further object of my invention is to provide a device of the character described in which means is provided for preventing the escape of cold air from the refrigerator when the device is not in use, as in the summer months.

15 A further object of my invention is to provide a device of the character described in which means is provided for preventing rain, snow, sleet and the like from entering 20 the refrigerator when the device is in operation.

25 A further object of my invention is to provide a device of the character described which is simple in form, compact, and thoroughly efficient for the purpose intended.

30 Other objects and advantages will appear in the following specification, and the novel features of the invention will be particularly pointed out in the appended claim.

35 My invention is illustrated in the accompanying drawings forming part of this application, in which I have shown a sectional view of an embodiment of my invention.

40 In carrying out my invention I make use of the ordinary type of refrigerator having a heat insulated wall 1. For efficient installation of my device I preferably place the refrigerator with its adjacent wall near to an outside wall 2 of the building or room in which the refrigerator is placed. I provide a horizontal opening 3 through the building wall 2 and an opening 4 through the adjacent wall of the refrigerator 1 in registration with the opening 3.

45 My improved cooling means consists in a fan chamber 5 having end walls 6 and 7 respectively, in the shape of a truncated hollow cone. The small or outer ends 8 of the end walls 6 and 7 respectively are connected with cylindrical air ducts 9 and 10 respectively. The air duct 9 is projected through the opening 4 and the air duct is projected through the opening 3. The outer end of the air duct 10, i. e., that end which is outside of the building may have an overhang-

ing canopy portion 11 which falls to a point at 12 common with the plane of the lowermost wall of the duct 10.

50 A fine mesh screen 13 is disposed over the mouth of the duct 10 so that birds, insects and the like may not be drawn into the ice box with air passing therethrough when the device is in operation.

55 A fan 14 is disposed in the air chamber 5 and is supported upon the axle shaft 15 of an electric motor 16. The motor 16 is centrally disposed and fixed within the air chamber 5 by means of rods 17 secured at their outermost ends to the inner wall of the chamber 5 and at their innermost ends to 70 the shell of the motor 16. Electrical conducting cords 18 for supplying current to the motor 16 are connected thereto and projected through an insulating bushing 19 in the end wall 7 of the chamber, whereupon 75 they are connected to a suitable current source (not shown). A switch may be disposed in the circuit of the motor 16 for the purpose of controlling the operation of the motor.

80 The innermost end of the air duct 9 i. e., that end projected within the refrigerator is cut off obliquely, as shown at 20, and a light metal cover 21, hingedly mounted at 22 to the duct 9, is disposed thereupon so 85 as to normally close the inner end of the duct when air is not passing therethrough.

85 When the fan 14 is in operation, however, the passage of air through the chamber 5 will follow the course of the arrows 23, and 90 cause the cover 21 to assume the position shown in dotted lines. This is due to the fact that the cover plate is extremely light, preferably of aluminum, and the current of air causes the door to lift from its seat 95 upon the inner end of the duct.

95 From the foregoing description of the various parts of the device the operation thereof may be readily understood. My invention is primarily intended for use during the winter months when the temperature of the atmosphere is very low and intended to eliminate entirely the use of artificial cooling means within the refrigerator. Operation of the motor 16 will draw air 100 from outside the chamber 5 into the refrigerator where it will serve to cool the contents by absorbing the heat, in the same manner as cool air is emitted from ice or artificial cooling mediums.

The fan 14 may be operated manually, i. e., the motor 16 turned on or off when desired, or a thermostatic switch may be employed to maintain the temperature uniformly. Such a switch is well known in the art and needs no explanation here. At all times when the motor 16 is not operating the passage of air from the refrigerator out through the duct 10 in the reverse direction is prevented, due to the fact that the cover 21 will assume the position shown in full lines by virtue of its own weight.

The canopy portion 11 of the duct 10 effectually prevents the entrance of rain, sleet, snow and the like to the refrigerator, and the screen 13 guards against the admission of small insects, birds, and the like which might be drawn in through the duct when the fan is in operation.

I claim:

A device of the type described comprising an air exhaust duct having a relatively large end and a relatively small tapered end, a flap hingedly secured to the upper portion of said air duct for normally closing said duct, an air intake duct having a relatively large end and a relatively small end, the upper portion of the relatively small end of the intake duct being bent outwardly and downwardly to a point in alignment with the lower surface of said duct, a cylinder rigidly secured to said relatively large ends, a motor disposed in said cylinder, and a relatively large fan disposed in said cylinder and operatively connected to said motor.

GUSTAV ADOLPH STREHLKE.
